UNITED STATES PATENT OFFICE.

WELBY W. BURGIN, OF RICHMOND, KENTUCKY.

DENTIST'S TWEEZERS.

No. 836,299.

Specification of Letters Patent.

Patented Nov. 20, 1906.

Application filed February 11, 1904. Serial No. 193,091.

To all whom it may concern:

Be it known that I, WELBY W. BURGIN, a citizen of the United States, residing at Richmond, in Madison county, State of Kentucky, have invented certain new and useful Improvements in Dentists' Tweezers, of which the following is a specification.

My invention relates to pliers or tweezers especially adapted for dentists' use, and is particularly designed for the handling of gold in cleaning and purifying it by heat and acids.

The objects are to provide the tool with points or tips adapted to hold small particles firmly and capable of being plunged into the flame and the acid without tarnishing or injuring the gold, and to provide the tool with improved means for registering the points and for holding the jaws together.

In the accompanying drawings, Figure 1 shows in perspective a tool embodying my several improvements, and Fig. 2 is a section of the sheath on the point of the jaw.

In dental work it will be understood that it is necessary to thoroughly clean and purify the small bits of gold used for filling just prior to their insertion in place, which is done by first heating the gold and then immediately plunging it into a strong acid and then washing. If ordinary steel pliers were used, the heating and the acid invariably causes a deposit of injurious chemicals on the part of the gold which is in contact with the tool, which of course causes waste of gold and soon renders the tool unfit for use and is generally disadvantageous. I find that providing the tips of the tool with a platinum sheath fixed on in a peculiar way avoids all these difficulties, because platinum is not affected by the acid, makes no deposit on the gold, and easily withstands the high degree of heat.

In the drawings, the two arms 1 are tipped with sleeves 2, formed of platinum tubes, made to neatly fit the steel points throughout and secured thereon by any desirable

means. One of the arms is provided with a stud or pin 5, which registers with the hole 6 in the other arm in order to bring the fine points accurately together. Both arms are 50 provided with slots 3, in which is placed a sliding bolt 4, which when the arms are pressed together easily slides downward in the slots and holds the jaws together.

It will be observed that by this construction the points of the steel tool which are exposed to the acid in use are entirely protected by the platinum and that the platinum points are rigidly supported down to their extreme ends. The result is that no chemical deposit is made upon the gold, and therefore there is no waste in the use of this material.

Having thus described my invention and its use, what I claim as new, and desire to 65 secure by Letters Patent, is the following:

1. As an article of manufacture, a pair of spring-jaws and means to register them together, said jaws having fine tapered points of steel, and each having a sheath of non-corrosive and relatively infusible material such as platinum formed as a closed tube and covering the sharp points neatly to their extreme ends, substantially as described.

2. The combination with a pair of tweezers 75 having pointed jaws, and means for accurately registering them, of tapering closed tubular sheaths on said points composed of platinum and fitting and supported by the hard metal points to their extreme ends, 80 whereby said points may be used in acids and flame without corrosion and are adaptable to very small objects, substantially as described.

In testimony whereof I have signed my 85 name to this specification in the presence of two subscribing witnesses.

WELBY W. BURGIN.
